UNITED STATES PATENT OFFICE.

GEORGE J. PARHAM, OF BEDFORD, INDIANA, ASSIGNOR TO THORNTON & PARHAM, OF SAME PLACE.

HAND-REAPER.

SPECIFICATION forming part of Letters Patent No. 310,537, dated January 6, 1885.

Application filed July 18, 1882. (No model.)

To all whom it may concern:

Be it known that I, GEORGE J. PARHAM, of Bedford, in the county of Lawrence and State of Indiana, have invented certain new and useful Improvements in Hand-Reapers; and I do hereby declare that the following is a full, clear, and exact description thereof, reference being had to the accompanying drawings, and to the letters of reference marked thereon, which form part of this specification, in which—

Figure 1 is a top plan view; Fig. 2, a bottom plan, and Fig. 3 a side elevation.

This invention has for its object the toppling of grain, and is designed to be operated by hand-power.

Its novelty consists in the combination and arrangement of certain well-known elements, whereby the object in view is accomplished with a minimum of labor.

To enable others skilled in the art to avail themselves of the benefits of my invention, I will now proceed to describe its construction and operation.

25 A A represent handles, between which the operator stands and pushes the machine as he would a wheelbarrow. To these handles are securely bolted metal plates, B B, upon the front end and upper side of which is secured 30 the finger-bar C, which is slotted to enable the cutter-bar D to be fastened to it, and yet vibrate in the usual and well-known way.

E represents a revolving axle, which extends through the metal plates B B, and to the ends 35 of this axle are secured the driving-wheels F F'.

To the axle, and upon the inner side of the wheel F, is secured the gear-wheel G, which I prefer to have about one-half of the diameter of the driving-wheels, as it is from the wheel 40 G that the endless apron and cutter-bar receive their motion.

On the outer end of the axle E, by the side of the driving-wheel F, is fixed the pulley a, around which passes the belt or cord b. This 45 cord also passes around the pulley c on the end of the reel-shaft, and thus is motion communicated to the reel H, which is supported above the finger-bar by means of the uprights d d.

e represents a revolving shaft journaled in 50 the plates B B. One end of this shaft is provided with the pinion f, which meshes in the

gear-wheel G, while at or near the opposite end of this shaft is secured the side or beveled cog-wheel, g.

h is a crank-shaft which extends in a line 55 parallel to the side plates, B B, and is journaled in cross-plates x x, which brace the side plates, as seen in Fig. 2. The crank-shaft h is provided with a pinion that gears with the beveled cog-wheel g, while to the opposite end 60 of said shaft is secured the metal wheel or disk i. On the outer face of this disk i is a wrist-pin, and from this pin to a staple on the under side of the cutter-bar extends the pitman K. Thus it will be seen that a vibratory motion 65 is conveyed to the knives or cutter-bar as soon as the machine is put in motion.

The frame of the machine is provided with a suitable floor, which extends forward almost to the finger-bar and rearward to a line just 70 behind the wheels, and at this latter termination a trough is formed, as seen at letter M, to catch the grain as it is conveyed back by an endless apron, C'.

B' B' represent shields which extend upward 75 to the height of the wheels, so as to prevent the grain from falling off and getting into the gearing.

C' represents the endless apron which extends around the rollers n n'. These rollers 80 are journaled in the shields B' B', and to the rear roller, n', is attached the pinion p, which meshes with gear-wheel G.

It will be observed from the preceding description that, the operator standing between 85 the handles and pushing the machine as he would a wheelbarrow, the whole train of mechanism will be set in motion, and as the grain is cut by the vibrating knives the reel pushes it upon the apron, which carries it along and 90 deposits it into the trough, to be taken therefrom when full.

It will be observed that I have a hand-reaper or topper the frame of which is constructed of two handles, two side bearing-plates having 95 shields on the sides, and two brace-bars for the said side plates, which also serve as bearings for the crank-shaft h. Such frame is essential in carrying out my invention. It will also be observed that I combine with such 100 frame a front cutting apparatus, a reel, an endless carrier, and a rear depressed receptacle,

all of which are necessary to effect the objects set forth.

Having thus fully described my invention, what I claim as new, and desire to secure by 5 Letters Patent, is—

In a hand-reaper mounted on wheels F F', a frame consisting of rear handles, side plates, front and rear braces, and side shields secured to the side plates, in combination with a cutting apparatus applied to the front ends of 10 said side plates, a revolving reel arranged

over the same, an endless apron, and a rear depressed receiving-trough, all constructed, arranged, and adapted to operate substantially in the manner and for the purpose described. 15

In testimony that I claim the foregoing as my own I affix my signature in presence of two witnesses.

GEORGE J. PARHAM.
